Attorney

UNITED STATES PATENT OFFICE.

LEMMA J. ROOT, OF SEATTLE, WASHINGTON.

FLUID BRAKE.

Application filed December 11, 1919. Serial No. 344,231.

To all whom it may concern:

Be it known that I, LEMMA J. Root, a citizen of the United States, residing at Seattle, in the county of King and State of Washington, have invented certain new and useful Improvements in a Fluid Brake, of which the following is a specification.

This invention relates generally to fluid clutches and more particularly to that type of clutches designed to retard or check the rotary movement of a shaft, or other rotating element, or to effect transmission of power from a drive element to a driven element.

15 The principal objects of the invention are: first, to devise a clutch of the type indicated wherein the clutching action may be increased or decreased to retard or accelerate the rotation of a shaft or other rotating element between the maximum—full speed, or the minimum—a complete stop; second, to effect transmission of power from a drive shaft to a driven shaft; third, to effect a clutching action without coincident 20 shocks as in devices at present used for a like purpose; and fourth, to decrease frictional wear on the clutch element.

With these and other objects in view as will appear in the following description taken in connection with the accompanying drawings the invention comprises the various novel features of construction and arrangement of parts, which will be more fully described hereinafter and set forth 35 with particularity in the claims appended hereto.

In the drawings:—

Figure 1 is a transverse section of the invention, and

40 Figure 2 is a slight modification of the piston and valve construction.

Figure 3 is a detail of the eccentric connections, shown in Fig. 1.

45 Corresponding parts in the several figures are indicated by similar characters of reference.

Referring particularly to Fig. 1 of the drawings, wherein is illustrated the device as adapted to retard or stop the rotation of a shaft, shown at 16, a centrally disposed case or eccentric housing A, having an upper convex wall 1 and a lower concave wall 2, terminates in opposed cylinders 3 provided in the upper and lower portions of their outer ends with outlet and inlet ports 4 and 5 respectively and seated within

which are outlet valves 6 and inlet valves 7. The cylinders are connected intermediate their extremities with a casing 8 having a centrally convex top 9 and provided with a centrally convex partition 10 dividing the interior thereof into what I shall term a circulation chamber B and a compression chamber C communicating through the inlet and outlet ports 5 and 4 in a manner which will be hereinafter described. A hollow sleeve or cylinder 11 the top portion of which is provided with a flange opening 11^b, is mounted on the partition 10 and communicates with the compression chamber C through an opening 12 formed therein. The sleeve 11 extends upwardly through the top 9 of the casing 8 and is provided with an opening 13 communicating with the chamber B. A trunk valve 14 connected by a rod 15, extending through the opening 11^b, and secured to a suitable operating lever (not shown) is slidably mounted in the sleeve 11 for controlling communication between the chambers C and B for a purpose which will hereinafter appear.

The shaft 16 the rotation of which is to be controlled by the clutch constituting this invention to be of any conventional type and extends through the housing A and has fixedly mounted thereon an eccentric 17 about which are mounted straps 18 rigidly connected as at 19 to piston rods 20 which pivotally engage as at 20' piston heads 21 operating in the cylinders 3.

The operation of this form of the invention is as follows:—

Normally the valve 14 is disposed in an open position, as shown in Figure 1, and upon rotation of the shaft 16 the pistons 21 will be reciprocated in the cylinders 3 drawing in fluid which may be a suitable fluid from the circulating chamber B through inlet valves 5 and expelling it into the compression chamber C through outlet valves 4, and as communication is established between the chambers C and B through openings 12 and 13 (the valve 14 being open) a circulation will be effected between the two chambers which will not hinder or retard the operation of the pistons (the size of the chambers and valves being sufficiently large to permit of free circulation). However, when the valve 14 is moved downwardly in the sleeve 11 the opening 13 will be constricted and circulation will be retarded consequently retarding the action of the pis-

tons through fluid resistance due to increase of compression in the chamber C, and when the valve 14 completely closes the opening 13 the compression in the chamber C will increase until the pistons can no longer reciprocate and rotation of the shaft 16 will be stopped. It will be seen that as the valve 14 is moved downwardly the rotation of shaft 16 is gradually retarded until a complete stop is effected.

In the modification illustrated in Figure 2 the piston 21' is reciprocated in a cylinder 3' having double heads 22 forming compartments X and Y, provided with intake valves 5' and exhaust valves 6', so that upon movement of the compression stroke of the piston in compartment Y suction will be caused in the compartment X and vice versa thus utilizing for the pumping action only one piston and cylinder as compared with two in the preferred form illustrated in Figure 1.

From the foregoing description taken in connection with the accompanying drawings, it is thought that a clear and comprehensive understanding of the construction, operation, and advantages of the invention may be had, but while I have shown and described the device as embodying a specific structure, I desire it to be understood that changes may be made in said structure as do not depart from the spirit and scope of the invention as claimed.

What I claim is:

35 1. In combination with a rotatable shaft, means of the type described including pistons eccentrically connected with the shaft, a plurality of communicating chambers arranged within each other, one of said chambers receiving the pistons, valves for controlling circulation of fluid through said chambers upon reciprocation of the pistons, and a valve for closing communication between said chambers to induce compression 45 to retard reciprocation of said pistons to regulate the rotation of the shaft.

50 2. The combination with a drive element and a driven element, of a casing, partitions in the casing dividing the same into a circulating chamber and a compression chamber, valves for effecting communication between the compression chamber and circulating chamber, cylinders, pistons in said cylinders, eccentrically mounted on the other element, straps on the eccentrics connected with the pistons for reciprocating the

60 pistons upon rotation of the element on which they are mounted, to effect circulation of fluid from the circulation chamber to the compression chamber, a valve for opening and closing communication between the compression chamber and circulation chamber whereby to increase or decrease compression in the compression chamber for retarding or stopping the reciprocation of the 65 pistons to effect rotation of the casing with the element piston carried element, and the casing connected with the driven element for effecting more or less complete transmission of power from the drive to the 70 driven element.

75 3. The combination with a drive element and a driven element, of a casing, partitions in the casing dividing the same into a circulating chamber and a compression chamber, valves for effecting communication between the compression and circulating chambers, cylinders, pistons in said cylinders, eccentrically mounted on the drive element, straps on the eccentric connected with the pistons for reciprocating the pistons upon rotation of the drive element, to effect circulation of fluid from the circulation chamber to the compression chamber, a valve for opening and closing communication between the compression and circulation chambers whereby to increase or decrease compression in the compression chamber for retarding or stopping the reciprocation of the pistons to effect rotation of the 80 casing with the drive element, the casing being thereby connected with the driven element for effecting more or less complete transmission of power from the drive to the 85 driven element.

90 4. In combination with a drive element and a driven element, a brake mechanism mounted on the drive element and secured to the driven element, one of said elements having aligned chambers, means for effecting circulation of fluid through said chambers, check valves for controlling the circulation of the fluid through the chambers, and means connected with the drive element for compressing the fluid upon the shutting off of circulation, to effect a more or less complete transmission of power from the 100 drive to the driven element.

105 In testimony whereof I, affix my signature hereto.

LEMMAN J. ROOT.
